UNITED STATES PATENT OFFICE.

JAMES I. AYER, OF CAMBRIDGE, MASSACHUSETTS, ASSIGNOR TO SIMPLEX ELECTRIC HEATING COMPANY, OF BOSTON, MASSACHUSETTS, A CORPORATION OF MASSACHUSETTS.

APPARATUS FOR PRODUCING ELECTRIC ARCS FOR HEATING AND LIGHTING PURPOSES.

SPECIFICATION forming part of Letters Patent No. 748,574, dated January 5, 1904.

Application filed June 22, 1903. Serial No. 162,619. (No model.)

To all whom it may concern:

Be it known that I, JAMES I. AYER, a citizen of the United States, residing at Cambridge, in the county of Middlesex and State of Massachusetts, have invented an Improvement 5 in Apparatus for Producing Electric Arcs for Heating and Lighting Purposes, of which the following description, in connection with the accompanying drawings, is a specification, like letters on the drawings representing like parts.

My present invention is an improvement in the same general line of invention as disclosed in my copending application, Serial No. 15 161,436, and is another embodiment of the broad invention claimed in said application generically.

Besides other features of the invention I herein provide means for shifting the carbons 20 or electrodes after each use thereof, so as to bring a fresh contacting surface into operation for further use.

Without further explanation and referring to my aforesaid application for a further presentation of the general subject, my invention 25 will be fully understood by reference to the accompanying drawings, in which I have shown one embodiment thereof, and will be more clearly defined in the appended claims.

30 In the drawings, Figure 1 represents in front-elevation sufficient details of my invention to enable the same to be understood. Fig. 2 is a transverse horizontal sectional view thereof, taken on the line 2 2, Fig. 1.

35 At the front of the supporting plate or standard α is a carrying bar or frame α' , secured at α^2 (see Fig. 2) on the projecting arms α^3 of a lifting-bar or operating member α^4 , said arms operating in vertical slots α^5 in the 40 back plate or support α . Beneath the frame or carrier α' is a ledge α^6 , bearing at its free end a triangular or wedge shaped block α^8 , preferably of fire-clay or other suitable insulating material.

45 Slidingly mounted on the frame α' are opposite journal-blocks α^9 , in which are journaled cranks α^{10} , from the free ends of which project crank-pins or stub-shafts α^{12} , carrying electrodes, which are herein shown in the

form of carbon-wheels α^{13} , mounted on insulating-bushings α^{14} . To the rear side of each bushing is secured a ratchet-wheel α^{15} , engaged by a spring-pawl α^{16} , the crank α^{10} being restricted in its swinging movement by a pin α^{17} , engaging a notch α^{18} and normally held downward by a spring α^{20} and moved upwardly at proper times by the engaging of a pin α^{21} on the support α with a rod or arm α^{22} , which projects rigidly from the rear end of said crank. The two journal-bearings α^9 and the described parts carried thereby are normally moved inward toward each other by springs α^{23} .

Spanning across the upper side of the frame α' is a stop, herein shown in the form of a yielding strap or plate α^{24} , adapted to be engaged at times by the depending middle portion α^{25} of a stop α^{26} , secured at α^{27} to the back plate α . Spring-contacts $\alpha^{28} \alpha^{29}$ are provided for completing the electrical circuit by 70 contacting with the carbons when the latter are raised.

The operation of my invention is as follows: Normally the electrodes are in circuit-breaking position, as shown by the dotted lines x , Fig. 1, and when it is desired to create an arc the operator lifts on the bar α^4 , thereby raising the frame and all the parts carried thereby, whereupon the electrodes slide on the opposite inclined walls of the insulator-block α^8 , gradually approaching each other by reason of the springs α^{23} until they come into contact in the position shown at y . A further upward movement swings them into arc-forming position, as indicated at z . Slightly before they arrive at this point the carbons come into contact with the contact-springs $\alpha^{28} \alpha^{29}$, so that when the carbons arrive at the point y they complete the circuit. At this time the retarding device α^{34} is pressed by the stop α^{26} into holding engagement with the journal-blocks α^9 , preventing them from moving farther forward or changing position, and thereupon the rods α^{22} come into contact with the pins α^{21} , so that further upward movement (which is permitted by the yielding character of the stopping devices) causes the cranks α^{10} to turn on their shafts to the limited extent permitted by the

pins a^4 , thereby swinging the carbons away from each other a sufficient distance to produce the arc required. Having used the arc all that is desired, the operator permits the bar a^4 to descend, the first lowering movement of the cranks a^{10} causing the electrodes to rotate slightly by reason of the pawl-and-ratchet arrangement $a^{15} a^{16}$, and as soon as the carbons come into contact with the block a^8 they roll down the same instead of sliding, as they did in going up. This brings a new carbon-surface into position for the next time an arc is required.

The feature of swinging the electrodes away from each other after they have come into circuit-closing position is broadly claimed in my aforesaid application, where various fields of usefulness of the present device are also explained. It will also be understood that the present mechanism may be employed with various other features shown in my aforesaid application.

While I have herein shown the preferred embodiment of my invention in its various details, I wish it understood that many changes in form, arrangement, and combination of parts may be resorted to without departing from the spirit and scope of my invention.

Having described my invention, what I claim as new, and desire to secure by Letters Patent, is—

1. In an apparatus of the kind described, a rotary electrode, a surface against which it may bear, a support for said electrode, means for rolling said electrode along said surface, and means permitting the electrode to roll along said surface in moving in one direction and for preventing said turning in moving in an opposite direction.

2. In an apparatus of the kind described, opposite electrodes for producing an arc, carrying means manually operated for moving said electrodes bodily up and down, and means coöperating with one of said movements for automatically separating said electrodes and

permanently breaking the circuit.

3. In an apparatus of the kind described, opposite electrodes for producing an arc, means holding said electrodes normally separated, carrying means for moving said electrodes bodily up and down, means coöperating therewith for permitting said electrodes to come together, and means for thereafter moving said electrodes apart to form an arc.

4. In an apparatus of the kind described, opposite electrodes normally separated and out of circuit, carrying means for moving said electrodes bodily up and down, and means coöperating therewith for automatically separating said electrodes to form an arc.

5. In an apparatus of the kind described, opposite electrodes for producing an arc, carrying means for moving said electrodes bodily up and down, means coöperating therewith for automatically separating said electrodes to form an arc, and automatic means normally

tending to move said electrodes into position for permanently breaking said arc and cutting out the current therefrom.

6. In an apparatus of the kind described, opposite electrodes, one of said electrodes having yielding means, normally pressing the same toward the other electrode, and mechanical means for automatically moving said electrode away from said position.

7. In an apparatus of the kind described, opposite electrodes, one of said electrodes having yielding means, normally pressing the same toward the other electrode, separating means for thereafter moving said electrode to arc-forming position, and means for holding said electrode against the action of the pressing means while being acted upon by said separating means.

8. In an apparatus of the kind described, an electrode, a manual lifting device therefor, a swinging arm on said lifting device, said electrode being carried at the free end of said arm, means for stopping the lifting movement of said device, and means for thereafter swinging said arm and electrode.

9. In an apparatus of the kind described, opposite electrodes, a manually-movable support for bodily lifting them, means coöperating therewith for normally moving them toward each other, and means for moving them into arc-forming position after they have come into circuit-closing position.

10. In an apparatus of the kind described, a pair of electrodes, manual means for moving them bodily upward, means coöperating therewith for permitting them to come into circuit-closing position, and means for thereafter separating them to form an arc.

11. In an apparatus of the kind described, a rotary electrode, a surface against which it rolls, a spring normally holding said electrode against said surface, means for bodily moving said electrode on said surface, and a co-operating electrode.

12. In an apparatus of the kind described, opposite electrodes, means for moving them up and down, means normally holding them yieldingly toward each other, and a wedge-shaped insulating-block in the path of said electrodes for automatically separating them.

13. In an apparatus of the kind described, a frame, opposite electrodes longitudinally movable on said frame, means for raising and lowering said frame, and means including a wedge-shaped device for mechanically separating said electrodes.

14. In an apparatus of the kind described, a pair of electrodes, manual means including a wedge-shaped device for bodily moving said electrodes to inoperative position, means coöperating with the aforesaid mechanism for moving said electrodes into circuit-closing position upon movement from said wedge-shaped device, and means for thereafter moving said electrodes into arc-forming position.

15. In an apparatus of the kind described, a frame, journal-blocks movable thereon,

cranks journaled therein, electrodes swinging on the free ends of said cranks, means normally moving said blocks toward each other, means automatically holding said blocks when moved to a predetermined position, and means for thereafter swinging said cranks and electrodes.

16. In an apparatus of the kind described, a frame, a journal-block, a crank journaled therein, an electrode swinging with said crank, means for moving said block on said frame, holding means for restraining said block against movement, and means for automatically swinging said crank.

17. In an apparatus of the kind described, a frame, a journal-block, a crank journaled therein, an electrode swinging with said crank, means for moving said block on said frame, holding means for restraining said block against movement, and means for au-

tomatically swinging said crank into one position, means for swinging said crank and electrode back again, and automatic mechanism for turning said electrode as it swings back.

18. In an apparatus of the kind described, opposite electrodes manually controlled, means for moving them toward each other, and mechanical means for swinging them apart, a frame carrying the aforesaid apparatus, and a supporting plate or standard over which said frame is movable.

In testimony whereof I have signed my name to this specification in the presence of two subscribing witnesses.

JAS. I. AYER.
